UNITED STATES PATENT OFFICE.

RICHARD K. HOHMANN, OF SAN DIEGO, CALIFORNIA.

TAKE-UP FOR SEWING-MACHINES.

1,073,489.

Specification of Letters Patent. Patented Sept. 16, 1913.

Application filed December 3, 1910. Serial No. 595,529.

To all whom it may concern:

Be it known that I, RICHARD K. HOHMANN, a citizen of the United States, and resident of San Diego, county of San Diego, 5 State of California, have invented certain new and useful Improvements in Take-Ups for Sewing-Machines, of which the following is a specification.

This invention relates to the take-up for 10 sewing machines and has been particularly designed for use in a rotary sewing machine in which the lower thread holder carries an ordinary spool of thread.

It has been my object to so time the parts 15 and to so regulate the speed of motion of the take-up in the cycle of its movements as to more accurately and efficiently form the loop to be engaged by the lower thread looping means and to supply the proper length of 20 thread at the right time in order to pass freely around the bobbin.

The novel features of the invention will 25 be apparent from the following description taken in connection with the accompanying drawings.

In the drawings, Figure 1 is a face view 30 of the head of the machine having the face plate removed and showing my invention applied thereto; Fig. 2 is a detail front view 35 of the take-up mechanism removed.

In the drawings 1 represents the ordinary head of a sewing machine in which is mounted the vertically reciprocating needle bar 2 and also the presser foot bar 3. These 40 parts are of the usual construction and need not be described in detail.

In the frame of the machine and extending into the head there is a rotary shaft which has within the head two separate 45 crank arms which carry the crank pins 4 and 5. In the particular form shown the crank arms are in the shape of circular disks, one behind the other in Fig. 1, but it will be understood that the particular form 50 of these arms is no part of my present invention. The crank pin 4 has pivotally secured thereto a link 6 which is pivotally secured at its other end to the needle bar 2, so that the rotation of the shaft and crank 55 serves to reciprocate the needle bar in order to form the stitch. The crank pin 5 is on the face of the crank arm or disk 7 and it preferably carries a roller for the purpose of reducing friction and this is the roller 60 which operates the take-up mechanism of the machine. One arrangement of mecha- 65 nism by which the crank arms are supported is illustrated in my prior Patent No. 977,630, but it will be understood that the invention is not confined to that particular form. 70 The take up in the particular form shown embodies a take-up shaft 8 and an arm 9 which extends out to the side of the head of the machine and carries at its outer end an eye 10 to receive the thread. Another arm 11 extends from the take-up shaft and is provided with an irregularly shaped slot in which the pin 5 works and it will be seen by reference to Fig. 1 that the shaft of the take-up device is mounted just beyond the 75 edge of the circular path in which the pin 5 moves so that at one point of its revolution the pin 5 approaches the pivot of the take-up very closely and this occurs during the upward movement of the pin 5. The result 80 of this is that the take-up is quickly raised and the structure is such that practically all of the upward movement occurs during one-fourth of the revolution of the pin 5. The slot in the arm 11 is practically straight 85 from its inner end next to the shaft 8 out to the point 12 near the center where it takes an upward bend, thus forming what may be termed a hump from the point 12 to the point 13. From the point 13 to the outer 90 end the slot has a uniform downward curve. The purpose of the upward bend or hump is to give to the take-up a slight movement downward at a time just before such downward movement would commence if a 95 straight slot were used and by means of this upward bend the downward motion of the take-up is accelerated at the beginning so as to supply the necessary thread for use in forming the loop to be engaged by the rotary mechanism below the table. It will be observed that when this arm 11 is in its lowest position, the upward bend will have the reverse effect and will tend to give to the take-up a dwell in its lowest position. 100 In other words the bend will tend to give to the take-up a downward impulse when the arm 11 starts on its upward movement so that the resultant effect of the bend and the upward movement of the arm will be practically a dwell. It will further be observed from Fig. 1 that the downward motion of the take-up is accelerated by the hump when the needle bar has moved about half way down and is just entering the cloth. 105 The loop which is to be engaged by the rotary hook beneath the cloth must be formed 110

after the needle goes through the cloth and commences its upward movement and I have found by experiment that an accelerated supply of thread when the needle enters the 5 cloth greatly improves the results and prevents the skipping of stitches and the breaking of the thread. It permits a more perfect formation of the loop to be engaged by the hook. In Fig. 1 the relative positions 10 of the take-up arm and the link 6 are shown in dotted lines, the full line position of link 6 being omitted to avoid confusion in the illustration. The pins 4 and 5 are about 170° apart in the circle of their movement 15 and the result is that the pin 5 reaches the upward bend in the take-up before the needle bar reaches the lower limit of its movement and thus the take-up is given its initial downward movement so as to supply an excess of the thread just at the time when it is needed. I have found that this form of 20 take-up is very efficient when used in connection with the large bobbin holder for the lower thread constructed to receive an ordinary spool of thread since in that case the 25 loop must be large and sufficient thread must be supplied at the proper time to form it.

It will be understood that the particular 30 form of the take-up mechanism is not essential to my invention in its broad aspect, so

long as there is the rotary pin and the co-operating irregularly shaped cam surface on the take-up to give the peculiar motion and timing above described. 35

In my prior Patent 977,630 I have shown how the slotted arm and take-up arm are connected and mounted and therefore it is not necessary in the present case to specifically illustrate that construction. 40

Having described my invention what I claim and desire to secure by Letters-Patent is,

In a sewing machine, the combination with a rotary crank having a crank pin, of 45 a take-up rock shaft mounted in bearings just beyond the circular path of said pin and approximately on a level with the lower limit of the movement of said pin, and an arm extending from said rock shaft having 50 therein a slot in which said pin works, the said slot being straight in that portion next to the shaft having an upward curve or hump near its center and a downward uniform curve from the center to the outer end. 55

In testimony whereof I affix my signature in presence of two witnesses.

RICHARD K. HOHMANN.
